(57) **CLAIM**

I claim the ornamental design for a dog diaper, as shown.

DESCRIPTION

The design includes the center layer of composite fiber material and two flanking layers of polyethylene material. A hole is located in the center layer of composite fiber material.

FIG. 1 is a front view of the dog diaper;

FIG. 2 is a back view of the dog diaper;

FIG. 3 is a right view of the dog diaper;

FIG. 4 is a left view of the dog diaper;

FIG. 5 is a top view of the dog diaper; and,

FIG. 6 is a bottom view of the dog diaper.
